UNITED STATES PATENT OFFICE.

WILLIAM H. POTTORF, OF MASON CITY, ILLINOIS.

CONCRETE-MIXER.

1,119,634.

Specification of Letters Patent.

Patented Dec. 1, 1914.

Application filed May 9, 1913. Serial No. 766,617.

To all whom it may concern:

Be it known that I, WILLIAM H. POTTORF, a citizen of the United States, residing at Mason City, in the county of Mason and 5 State of Illinois, have invented new and useful Improvements in Concrete-Mixers, of which the following is a specification.

The invention relates to a mixing machine and more particularly to the class of concrete mixers.

The primary object of the invention is the provision of a machine wherein the mixing chute may be angularly adjusted to various degrees to assure the delivery of the mixture after being agitated, that is to say, the material during the mixing thereof will be precipitated from the receiving end to the discharge end of the machine.

Another object of the invention is the 20 provision of a machine of this character wherein the agitating reel is of novel construction to assure the proper and uniform mixing of the material delivered into the machine.

A further object of the invention is the 25 provision of a machine of this character wherein water will be delivered to the mixer from one side thereof.

A still further object of the invention is 30 the provision of a machine of this character which is simple in construction, thoroughly reliable and efficient in its operation and inexpensive in manufacture.

With these and other objects in view, the 35 invention consists in the construction, combination and arrangement of parts as will be hereinafter fully described, illustrated in the accompanying drawing, and pointed out in the claim hereunto appended.

40 In the drawings:—Figure 1 is a side elevation of a machine constructed in accordance with the invention. Fig. 2 is a top plan view thereof. Fig. 3 is a vertical longitudinal sectional view of the same. Fig. 4 is a sectional view on the line 4—4 of Fig. 2. Fig. 5 is a rear elevation.

Similar reference characters indicate corresponding parts throughout the several views in the drawing.

50 Referring to the drawings by numerals, the machine comprises a rectangular shaped frame 10 which is preferably constructed

from wood, although it may be made from any other material, and to the cross end rails 11 of which at the under side thereof are fixed central bearings 12 having journaled therein the operating shaft 13 of a mixing or agitating reel presently described. Built at one end of the frame 10 is a hopper 14, and on one side of the latter and fixed to the frame are bridge pieces 15 to one of which is hinged a door 16, it being seen that the major portion of the frame 10 at the top thereof is closed, yet access may be had through the door 16 to the metal mixing and delivery chute 17 which is in the form of a semi-circular body, the longitudinal edges of which are suitably secured to the inner faces of the side rails of the frame 10 and into this chute 17 is poured the concrete material to be mixed with water, in a manner presently described. At the hopper end of the frame 10 and pivoted to the sides thereof are swinging prongs or legs 18 whereby the frame and chute 10 and 75 17 respectively can be angularly adjusted, thus permitting the elevation of the hopper end to precipitate the material delivered into the chute toward the discharge end thereof. The mixing reel comprises a plurality of 80 spiders 19 which are arranged in spaced relation to each other and are centrally fixed to the shaft 13, and on the outer ends of the arms of the spiders 19 are fixed rods 20 which act upon the concrete material for 85 mixing and agitating the same when being precipitated within the chute from the hopper to the discharge end thereof, the shaft 13 being provided with a pulley wheel 21 which is rotated from any suitable motor. 90 Formed in the upper edge of one side of the frame 10 is a notch 22 providing a seat for a water nozzle 23 to which is adapted to be connected a water hose whereby the nozzle will feed water into the chute 17 for moistening or wetting the concrete material. 95

From the foregoing it is thought that the construction and manner of operation of the device will be clearly apparent, and therefore a more extended explanation has been 100 omitted.

What is claimed is:—

The combination with a mixer frame of substantially rectangular formation, of

lined bearings depending centrally from the end rails of the frame, a semi-cylindrical chute secured to the said rails of the frame and projecting below the bottom thereof, an 5 agitator shaft arranged in the chute and journaled in said bearings, a cover for said chute having a swinging door section, a feed hopper at one end of the frame, and a pair

of pivot legs supporting the hopper end of the frame in different elevated positions. 10

In testimony whereof I affix my signature in presence of two witnesses.

W. H. POTTORF.
